JOHAN EMIL HILLEBRANDT, OF BROOKLYN, NEW YORK

STRINGED INSTRUMENT

Application filed July 21, 1928. Serial No. 294,893.

My invention relates to musical instruments of the plectrum type, such as the mandolin, banjo and guitar.

The object of my invention is to provide an instrument of the plectrum type having a key-board similar to a mandolin, banjo or guitar, and having an amplifying metal body portion or resonator formed substantially as shown in the drawings forming a part of this application.

A further object is to provide the instrument with plates of wood or other suitable material which will rest against the body of the player of the instrument, and also plates which serve as hand and arm rests, said plates also serving to prevent direct contact of the body of the player with the vibrating parts of the instrument.

A further object is to construct and locate the relative parts so that the instrument will not be too long or bulky in appearance, and may be held on the lap of the player in a convenient position when the instrument is being played upon.

Referring to the drawings which form a part of this specification:

Fig. 1 is a plan view of an instrument embodying my invention.

Fig. 2 is an inverted plan view of said instrument with a base plate held in position thereon.

A indicates the neck and head of the instrument, which is made of wood and is provided with the usual finger-board A' having frets A² and strings A³ thereon, the number and arrangement depending on whether the instrument is to be a mandolin, a banjo or a guitar, etc.

A⁴ is a tubular metal extension member which is securely fastened to the neck and supports the same.

The neck with the finger-board thereon is held in position above the resonator by the extension member which is mounted above the resonator B and connected thereto by a number of thin metal brace-rods C, C etc. of rectangular cross section, which may be welded to the resonator and extension member to hold the parts together, or may be secured thereto in detachable relation by nut and

screw elements D—D etc. which connect with upwardly extending flanges E, E, formed by turning the edges of the sheet which forms the resonator, upwardly as shown, and extending longitudinally thereof to stiffen the same, and for this purpose I also insert a central strip K, of thicker and stiffer metal, the edges of which are turned upward to form flanges K', and I also may insert a further strip of sheet metal K² between each of said flanges to provide a thick stiff composite flange at each side of the strip K.

I prefer to make the body or resonator portion of thin resonant metal such as aluminium alloys, but may use brass or other suitable material.

A bridge-plate F, formed of a flat strip of metal is bent into the form shown, its lower end being firmly secured to the flanges E, E respectively, and a bridge G, of metal, is supported thereon. The strings are connected to keys H, at one end and to a tail piece G' at the other end in the usual manner. J indicates a metal strip which serves as a brace, being connected to one side of the extension member A⁴, and a rod A⁵ extends therefrom to an adjacent brace rod C. The resonator is open at its larger end and closed at its smaller end. The neck and its extension member extend over the resonator at an angle thereto as illustrated, so that when held in the lap, the key-board is in a convenient position for use. A number of thin plates made of wood are supported in spaced relation to the resonator, the bottom or base-plate being indicated by L.

The lower side-plate is indicated by M, and the hand-rest plate by N. The arm-rest plate is indicated by O, and each of the plates is located and held in such a manner as to prevent the hand or body of the player from resting against the resonator. The supporting strips are made of metal bands which are fastened to the respective plates by screws P—P as illustrated in Figure 2. The base-plate L is held in position by a band R, which extends therefrom over the top of the resonator and is secured to the top strip K, by screws R'. A band S also is connected to a brace-strip S' with which is in contact

and used to support the arm-rest O in position. The brace-band S' is secured at its upper end to the adjacent side of the extension member A⁴ as shown at S². A brace-band T is firmly secured to the under side of the extension member A⁴, by screws T', and is bent to the proper form to support the plates N and M to which it is attached, and its ends extend downwardly and are connected by screws (not shown) to the base-plate L.

A brace-band U extends from one side of the extension member under the plate N, and is bent inwardly parallel with its top portion at its lower end and connected to the base-plate L, its top end being connected to the extension member. While I have shown the brace-bands connecting the parts as illustrated, I do not wish to be limited to the specific construction shown in this respect, as the plates may be connected together and to the resonator and extension member in any manner that will hold them in proper spaced relation with the resonator.

I have provided the base-plate with longitudinally extending ribs V, V, etc. spaced apart as illustrated, which serve to prevent the plate from shifting or sliding over the clothing of the player, and also serve to stiffen and strengthen the plate, and also provide the necessary thickness to hold the screws which connect the brace-bands to the plate. The several plates are formed with curved edge portions as shown, so that the instrument may be conveniently held in proper position for playing thereon.

The extension member A⁴ is a tube, preferably formed substantially rectangular in cross section and about one sixteenth of an inch in thickness, but it may be made in any suitable form, and may be made of wood if desired.

The large end of the resonator is provided with a bead X, to stiffen the end of the instrument.

Short cross braces of band shaped metal W, are used to support the side flanges E, E, respectively, where required.

The instrument has a rich sonorous tone and provides a large volume of sound.

Having thus described my invention I claim as new:

1. A stringed musical instrument comprising a metal resonator closed at one end thereof, a neck having a key-board connected thereto adjacent said closed end and extending at an angle to the median line of said resonator, and a base-plate held in spaced relation to said resonator.

2. A stringed musical instrument comprising a metal resonator closed at one end thereof, a neck having a key-board connected thereto adjacent said closed end and extending at an angle to the medial line of said res-

onator, and a hand-rest plate held in spaced relation to said resonator.

3. As stated in claim 2: together with a side-plate held in spaced relation to said resonator.

4. A stringed musical instrument comprising strings and having a metal resonator closed at one end thereof and having longitudinally extending flanges formed on one side thereof, a neck having a metal extension member connected thereto and extending over said resonator at an angle to the median line thereof and spaced therefrom, and rods extending from said flanges to said extension member to hold the resonator and extension member together, and a base-plate and a hand-rest plate held in spaced relation with said resonator.

5. A stringed musical instrument comprising a metal resonator closed at one end thereof, a neck having a key-board connected thereto adjacent said closed end and extending at an angle to the median line of said resonator, a base-plate held in spaced relation to said resonator said plate having longitudinally extending ribs on its under side for the purpose set forth.

In testimony whereof I have affixed my signature.

JOHAN EMIL HILLEBRANDT.
